UNITED STATES PATENT OFFICE.

HARRY WILLIAM GAIN, OF TORONTO, ONTARIO, CANADA, ASSIGNOR TO FREYESENG CORK COMPANY, LIMITED, OF TORONTO, ONTARIO, CANADA, A CORPORATION OF ONTARIO, CANADA.

LIFE-PRESERVER.

1,301,831.

Specification of Letters Patent. Patented Apr. 29, 1919.

Application filed June 11, 1918. Serial No. 239,428.

To all whom it may concern:

Be it known that I, HARRY WILLIAM GAIN, of the city of Toronto, in the county of York, in the Province of Ontario, Canada, 5 have invented certain new and useful Improvements in Life-Preservers, of which the following is the specification.

My invention relates to improvements in life preservers and the object of the invention is to devise a life preserver which will support the body in such a position in the water as to hold the mouth of the person clear above the normal water level and which will prevent any danger of the head 15 falling forward so that the mouth becomes immersed and which is readily adaptable to fit various sized persons and it consists essentially of the following arrangement and construction of parts as hereinafter 20 more particularly explained.

Figure 1, is a perspective view showing my life preserver applied.

Fig. 2, is an enlarged perspective detail of my preserver.

25 In the drawings like characters of reference indicate corresponding parts in the various figures.

1 indicates my preserver which is formed in rectangular shape and comprising front 30 and back apron-like portions 1^x and 2^x connected together by an intermediate flexible portion 3 preferably formed of canvas. The apron-like portions 1^x and 2^x are formed with a series of closed pockets 4, 5 and 6 35 containing cork or other suitable buoyant material, the pockets being arranged on each side of the vertical center line and spaced apart. 7 indicates an opening which extends across the flexible portion 3 and in between 40 the upper pockets 4 of the front and back aprons and through which the head and neck of the wearer are designed to pass. 8 and 9 indicate loops secured to the portion 3 at each side of the opening 7 adjacent to the upper edge of the pockets 4 of the back apron 2. 10 and 11 indicate loops secured to the front apron between the 45 pockets 4 and 5.

12 indicates a string or tape. A string or 50 tape 12 extends through each of the loops 10 and 11 and through the loops 8 and 9, the upper end of the tape 12 extending through the loops 8 and 9 and extending downwardly to the lower front edge of the 55 portion 3. 13 indicates cross pieces carried

by the free ends of the tapes 12 to prevent them drawing through the loops 10 and 11. 14 indicates a tape secured to the back apron 2 between the pockets 5 and 6.

When the preserver is placed in position 60 upon the wearer the wearer passes his head through the opening 7 so that the flexible portion 3 rests upon his shoulders, the apron 1^x depending in front over the chest and the apron 2^x down the back. When in this position the wearer grips the tapes 12 and draws them down thereby gathering the flexible portion 3 together into puckers as shown in Fig. 1, and the back apron 2 upward so that the upper pockets 4 thereof containing the 70 buoyant material rest upon the back portion of the shoulder as indicated in Fig. 1. The tapes 12 are then tied together into a knot or bow as at 12^x, the free ends depending. The tape 14 is then passed around the waist of the 75 wearer and around between the ends of the pockets 5 and 6 over the free ends of the tapes 12, the ends of the tape 14 being then tied into a knot 14^x. By this means the preserver is so positioned on the body of the 80 wearer that when he is in water his body will be supported in an inclined position, the buoyant material depending over his chest tending to draw the front of his body up toward the surface of the water with greater 85 force than that extending over the back and, therefore, holding the body in a backwardly inclined position, so that the mouth of the person is directed upward preventing any tendency of the head of the person falling 90 forward due to exhaustion and the mouth then sinking below the level of the water so as to drown him.

From this description it will be seen that I have devised a very simple device which 95 will insure that the head of the wearer is held in such a position that it will not fall below the water level, the body being inclined backward so as to hold the head in this position and which by drawing up the tapes to 100 the required extent will make the preserver readily adaptable to fit various sized persons.

What I claim as my invention is:

1. A life preserver comprising an apron-like portion having a central opening through which the head of the wearer is designed to extend and forming back and front apron portions extending respectively over the chest and back of the wearer, pock- 110

cts formed in the front and back apron portions containing buoyant material, loops secured to the intermediate portion of the apron in aline with the back portion of the 5 central opening, loops extending from the front apron portion and tapes secured to the intermediate portion of the apron in front of the loops adjacent to the central opening and adapted to pass rearwardly from their 10 point of attachment through the loops adjacent to the central opening and then forwardly and downwardly through the loops carried by the front portion of the apron whereby when the preserver is in position 15 upon the wearer the central portion of the apron can be drawn together over the shoulders and the back portion of the apron drawn upward on to the shoulders by the downward pull upon the tapes prior to tying 20 of the tapes together, and a tape secured to the back portion of the apron in proximity to its end and adapted to pass around the body of the wearer in front of the front portion of the wearer and to be tied together.

2. A life preserver comprising an apron-like portion having a central opening through which the head of the wearer is designed to extend and forming back and front

apron portions extending respectively over 30 the chest and back of the wearer, pockets formed in the front and back apron portions containing buoyant material, loops secured to the intermediate portion of the apron in aline with the back portion of the central 35 opening, loops extending from the front apron portion and tapes secured to the intermediate portion of the apron in front of the loops adjacent to the central opening and adapted to pass rearwardly from their 40 point of attachment through the loops adjacent to the central opening and then forwardly and downwardly through the loops carried by the front portion of the apron whereby when the preserver is in position 45 upon the wearer the central portion of the apron can be drawn together over the shoulders and the back portion of the apron drawn upward on to the shoulders by the downward pull upon the tapes prior to tying 50 of the tapes together, and means for securing the lower ends of the apron portions to the body of the wearer.

HARRY WILLIAM GAIN.
